US00D809558S

(12) United States Design Patent (10) Patent No.: US D809,558 S
(45) Date of Patent: * Feb. 6, 2018

(54) DISPLAY SCREEN OR PORTION THEREOF
WITH ICON

(71) Applicant: Samsung Electronics Co., Ltd., Suwon-si (KR)

(72) Inventors: Bowon Kim, Busan (KR); Jiwon Yoo, Yongin-si (KR); Eunsun Chae, Seoul (KR)

(73) Assignee: Samsung Electronics Co., Ltd., Suwon-si (KR)

() Term: 15 Years

(21) Appl. No.: 29/586,605

(22) Filed: Dec. 6, 2016

(30) Foreign Application Priority Data

Jul. 22, 2016 (KR) 30-2016-0035949

(51) LOC (11) Cl. 14-04

(52) U.S. Cl.

USPC D14/489

(58) Field of Classification Search

USPC D14/485-495

CPC G06T 13/80; G06T 15/02; G06F 3/0481;
G06F 3/04817

(57) CLAIM

We claim the ornamental design for a display screen or portion thereof with icon showing our new design.

DESCRIPTION

The sole FIGURE is a front view of a display screen or portion thereof with icon showing our new design. The dash-dash broken lines in the FIGURE showing portions of the display screen form no part of the claimed design.

1 Claim, 1 Drawing Sheet
